UNITED STATES PATENT OFFICE.

ANDERS ANDERSSON ROSENGREN, OF MÄLMO, SWEDEN.

TAPPING APPARATUS.

1,347,914.

Specification of Letters Patent.

Patented July 27, 1920.

Application filed December 5, 1919. Serial No. 342,860.

To all whom it may concern:

Be it known that I, ANDERS ANDERSSON ROSENGREN, a subject of the King of Sweden, and resident of 70^b Södra Förstadsgatan, 5 Malmö, in the Kingdom of Sweden, have invented certain new and useful Improvements in Tapping Apparatus, of which the following is a specification, reference being made to the accompanying drawings.

- 10 The present invention relates to an apparatus for filling bottles or other vessels with a liquid. A filling apparatus arranged in accordance with the present invention is characterized primarily by the fact that 15 both its receptacle for the liquid with which the vessels are to be filled and its device for the support of the vessels is rotatable around a vertical axis, or is carried by a vertical, continuously or intermittently rotating 20 shaft. Although such a filling apparatus is used in every case where bottles (or other vessels) are to be filled with a liquid, it is, however, particularly suitable for use in connection with a machine which automatically seals the bottles according as they are 25 filled.

On the accompanying drawings is shown by way of example a filling apparatus carried out in accordance with this invention; 30 the apparatus is shown combined both with a sealing (capsuling) machine and with a device for the feeding of empty bottles to the tapping apparatus. Figures 1 and 2 show the group consisting of the three above 35 mentioned main parts, viewed from two directions at right angles to one another (in Fig. 2, however, the feeding device for empty vessels has been omitted). Fig. 3 shows the same group in plan and partly in 40 section, while Fig. 4 shows a detail. Fig. 5 shows diagrammatically and in plan a modification of a plant in accordance with this invention. Fig. 6 is a vertical sectional detailed view of the valve.

45 By means of the feeding device 1 for the empty vessels, which device is an elevator of any ordinary construction and which therefore does not need to be particularly described, empty bottles are raised from 50 premises below up to the filling apparatus.

The feeding of empty bottles may, however, also take place by means of some other devices.

The sealing machine 2 is arranged in essential conformity with the applicant's 55 Swedish Patent No. 40,480, besides which it is provided with a device performed in accordance with the applicant's copending application bearing Serial No. 342,859, filed Dec. 5, 1919, for the feeding to it of bottles 60 filled in the filling machine, which bottles are to be sealed. Neither the sealing machine nor its feeding device need be more particularly described.

On the frame 2 of the sealing machine 1 65 is mounted a horizontal arm 3, the free end of which serves as a bearing 4 for a vertical shaft 5, on the lower end of which is fixed a worm wheel 6, into which engages a worm 7, mounted on an oblique shaft 8, 70 which is journaled in two bearings 9 and 10, the one of which is fixed to the arm 3 and the other mounted in the frame of the sealing machine 1. The shaft 8 carries a second worm wheel 11, which engages with a worm 75 12, mounted on a shaft 13 belonging to the sealing machine.

On its upper end the vertical shaft 5, which is driven by the above described device from the sealing machine, carries a receptacle 14 for the liquid (e. g. beer) with which the bottles are to be filled. The liquid is introduced into the receptacle through a tube 15 passing centrally down to its arched roof and which tube is joined air-tight onto 85 the roof in such a manner that the receptacle can rotate, while the tube is stationary. From the lower part of the receptacle project filling tubes 16, the downwardly bent parts of which are provided with slidable 90 valves 17 which alternately expose and cover openings in the filling tubes 16, when the bottles are pushed up around these tubes, or are moved away from them, whereby the valves regulate the flow of the liquid. If 95 desired chains 17' may be employed for limiting downward movement of the valve body 17.

The bottles, which are filled with liquid from the receptacle 14 are with their lower 100

- part placed in holders consisting of rings, sleeves 18 or the like, arranged around and carried by a nave 19, which is fixed on the shaft 5 immediately above the bearing 4.
- 5 The filling of the bottles takes place when the bottles move from the position A (Figs. 1 and 3), in which they are placed in the holders or sleeves 18, to the position B, where the bottles leave the holders, so that
- 10 the shaft 5 rotates about half a turn. The bottles placed in the holders are supported by bottoms 20, which consist of flaps pivoted to the lower edges of the sleeves 18 so that they may swing downwardly, said flaps
- 15 in ordinary cases being locked to the sleeves. When a holder with a filled bottle standing on its bottom or flap 20 has arrived at the position B, the locking device between the sleeve and the flap is acted upon automatically, so that the flap and consequently the bottle standing on it falls down. In the device shown, the falling bottle is received by a chute 21, by which it is led to one of the sleeves, movable in a radial direction, in the
- 20 bottle feeding device belonging to the sealing machine. By this sleeve the filled bottle is then carried into the position in the sealing machine in which it is sealed or capsuled, whereupon the bottle thus filled and
- 25 sealed is delivered to, and carried away by, a chute 22.
- On the drawings the locking device between the sleeve 18 and its bottom or flap 20 is shown to consist of a hook 23, which is
- 30 pivotally mounted on the sleeve and engages under the flap. In this engaged position the hook is held by a spring 24 which is attached to the material carrying the sleeves 18 and situated between them and the nave 19. From the bearing 4 projects an arm 25, with which the one hook after
- 35 the other comes into contact when the corresponding bottle is to be delivered, so that the hook is carried aside and the flap is lowered.
- 40 During the continued rotation of the shaft 5 the lowered flap impinges upon a roller 26, rotatably mounted on a spring 27, which is fixed on the arm 3. By the said roller the flap is returned to its original position.
- 45 The sealing machine from which—as above stated—the tapping apparatus is driven, receives power from a belt 28, passing around a pulley 29. Between the latter and the corresponding idler 30 the belt 28 is moved by means of a belt fork 31, which is shifted by displacing a bar 32, which at its end situated at the place of the operator is provided with a handle 33.
- 50 The plant can be managed by a single operator who has his place between the feeding device of the empty vessels of the elevator 1 and the sealing machine 2, and at the side of the filling apparatus which is sit-

uated between the two first-named main parts of the plant. In spite of the fact that the plant for its operation needs only a single operator, its output capacity is nevertheless very great—about 2,500 bottles fed forward, filled, sealed and carried away per hour. By doubling or manifolding the main members (such as the holders of the filling apparatus) of the several main parts of a plant, its output capacity can be doubled or manifolded. In Fig. 5 is thus shown a plant, the members of the main parts of which have been trebled, whence the output capacity of the plant has been rendered three times as great as the output capacity of the plant as shown in Figs. 1 to 3.

As will be seen the filling apparatus and the sealing machine work in time with one another, so that a bottle which has been filled in the filling apparatus and has been delivered by it, will immediately afterward be sealed (capsuled) in the sealing machine.

Having now described my invention, what I claim as new and desire to secure by Letters Patent is:

1. A filling apparatus for use in connection with capsuling or sealing machines including a main support, a vertical shaft journaled therein, a liquid containing receptacle mounted on the upper end of the shaft, valve controlled filling tubes extending from the receptacle, a bottle support connected to the shaft beneath the receptacle including a circle of bottle receivers, normally closed flaps swingably connected to the lower edge of each bottle receiver, stationary means for successively releasing the flaps during rotation of the bottle supports, means for receiving the bottles when released, and means engaged with the released flaps for returning the flaps to a closed position.

2. A filling apparatus of the character described including a support, a vertical shaft journaled therein, a liquid receptacle carried by the top of the shaft, valve controlled filling tubes projecting from the receptacle, a nave carried by the shaft beneath the receptacle, a circle of bottle receiving sleeves formed on the nave, flaps pivoted to the lower edges of the sleeves, spring controlled catches engageable with the flaps for normally retaining the flaps in a closed position, a stationary hook on the support and successively engaged by the catches for insuring of the release of the flaps, a bottle receiver carried by the support onto which filled bottles are successively deposited, and a rotatably and yieldingly mounted roller successively engaged by the released flaps for insuring of the successive return of the flaps to their closed positions.

3. The combination of a filling apparatus according to claim 2 and a machine for the

automatic sealing of the bottles filled in the apparatus, means for operably connecting the filling apparatus and sealing machine, the filling apparatus and the sealing machine working in time with one another in such a manner that a bottle filled in the filling apparatus is immediately afterward sealed in the sealing machine, and common

means for controlling the operation of the filling apparatus and the sealing machine. 10

In witness whereof I have hereunto set my hand in presence of two witnesses.

ANDERS ANDERSSON ROSENGREN.

Witnesses:
